Primary Examiner — Lakiya G Rogers*Assistant Examiner* — Harold E Blackwell, II(74) *Attorney, Agent, or Firm* — Adams Law Office;
Sharon Adams(57) **CLAIM**

The ornamental design for a tool organizer, as shown and described.

DESCRIPTION

FIG. 1 is a perspective view of the tool organizer.

FIG. 2 is a front elevational view thereof.

FIG. 3 is a top plan view thereof.

FIG. 4 is side elevational view, the opposite side elevational view being a mirror image thereof.

FIG. 5 is bottom plan view thereof; and,

FIG. 6 is a perspective view thereof, with the environmental surroundings illustrated with broken lines.

The broken line showing in FIG. 6 is for the purpose of illustrating the environmental surroundings, and forms no part of the claimed design. The superimposed broken lines showing may obscure parts of the solid line disclosure, however FIG. 1-5 show the claimed subject matter.
